Primary Examiner — Sheryl Lane*Assistant Examiner* — Catherine Posthauer(74) *Attorney, Agent, or Firm* — Polsinelli PC(57) **CLAIM**

The ornamental design for an attachable tube-shaped holder for holding a cane, as shown and described.

DESCRIPTION

FIG. 1 is a perspective view of the attachable tube-shaped holder in use.

FIG. 2 is a front perspective view of the attachable tube-shaped holder of FIG. 1.

FIG. 3 is a top plan view of the tube-shaped holder for holding a cane of FIG. 1.

FIG. 4 is a front view of the tube-shaped holder for holding a cane of FIG. 1.

FIG. 5 is a right side view of the tube-shaped holder for holding a cane of FIG. 1.

FIG. 6 is a left side view of the tube-shaped holder for holding a cane of FIG. 1.

FIG. 7 is a back view of the tube-shaped holder for holding a cane FIG. 1; and,

FIG. 8 is a bottom plan view of the tube-shaped holder for holding a cane of FIG. 1.

The broken lines are shown for the purpose of indicating portions of the attachable tube-shaped holder for holding a cane and environmental structure and form no part of the claimed design.
